UNITED STATES PATENT OFFICE.

FRANCIS J. STRAUB, OF NEW KENSINGTON, PENNSYLVANIA.

STRIPPER BLOCK MACHINE.

Application filed February 16, 1927. Serial No. 168,567.

This invention relates to improvements in the manufacture of hollow building material, as blocks, made from concrete aggregate. It has for its object to provide means for imparting compressive action to the aggregate within the mold and around the usual cores, in connection with co-operating movement of the cores themselves, downwardly in compressing and then upwardly to a limited extent in ejecting or stripping, with a final wiping action by further movement of the block against the cores. Such operation effects a trowelling action or movement not only between the inner mold surfaces and the outer wall of the block, but also between the cores and the contacting or inner faces of the block surrounding the resulting core openings. It also effects a more even distribution and quality to the aggregate, due to the frictional development of transverse forces, through the aggregate tending to overcome voids, etc.

The advantages of the invention reside in a more regular and compact disposition of the aggregate, preventing arching or objectionable openings, with even distribution, together with a more economical application of power in performing the several operations, particularly in ejecting.

30 In the drawings, showing one preferred embodiment of the invention:

Fig. 1 is a plan view, showing one side of a molding machine, including a single block cavity;

35 Fig. 2 is a vertical sectional view through the machine on the line II—II of Fig. 1, showing the mold filled and leveled and the presser plate elevated;

40 Fig. 3 is a partial side elevation of Fig. 2;

Fig. 4 is a partial view, similar to Fig. 2, showing the presser plate lowered within the top of the mold and compressing the loose aggregate, and with the cores correspondingly lowered;

45 Fig. 5 is a similar view, showing the presser plate removed, and the pressed block elevated to the extent of return upward movement of the cores;

50 Fig. 6 is a similar view, showing the finished block removed upwardly beyond the mold and its cores;

Figs. 7 and 8 are diagrams showing the

proportionate extent of trowelling action on the aggregate by frictional action of the 55 mold faces and core faces respectively.

The mold 2 of the machine is mounted on frame 3 and is provided with a vertically movable core bridge 4 supporting the cores 5. A pressing plate 6 of standard construction is connected by cross bars 7 with the outwardly swinging vertically movable side plates 8, of well known construction and operation, for imparting downward pressing action on the aggregate. 60

In the construction shown, cross bars 7 are provided with vertically arranged transverse temper screws 9 adjustably mounted in arm 7 and provided with securing lock nuts 10, whereby the thrust of screws 9 70 may be regulated and fixed.

As shown, the terminals of the screws 9 engage centralizing sockets in the tops of the cores, thereby avoiding any tendency of the cores to lateral movement under pressure. 75

Core bridge 4, instead of being fixedly held across underneath the mold as in usual construction, is slidably mounted on studs 11 tapped upwardly into the lower edges of the mold and extending downwardly 80 through the terminal edge portions of the core bridge, as shown. Studs 11 extend sufficiently far to provide ample range of movement of supporting springs 12 carried by lower lock nuts 13. 85

Springs 12 are sufficiently strong to provide cushioning resistance for the core bridge and its cores on downward movement, and to re-act thereagainst for elevation of these parts upon sufficient reduction of friction, as in ejecting the finished block. 90

That is to say, when the springs are compressed as in Fig. 4, and presser plate 6 is elevated, the springs are not sufficiently strong to lift the core bridge and to thrust 95 the cores upwardly because of friction until the finished block is correspondingly raised by suitable ejecting mechanism, as in Fig. 5.

Due to such internal friction against the cores, they will rise with the block at the 100 commencement of the ejecting movement, thereby reducing the initial necessary force.

Bottom plate 15 occupies its usual position in the lower portion of the mold, for support of the usual bottom pallet 16, and 105 after pressing such bottom plate and pallet

are elevated for removal, as is generally understood and practiced in machines of this kind.

With the machine constructed as above described, and with the cores 5 held upwardly in their normal erected position within the mold, as in Fig. 2, the mold cavity surrounding the cores is filled with aggregate flush to the top, the presser plate 6 being temporarily thrust out of the way laterally and then brought back for downward pressure. As the presser plate and its parts move downwardly, screws 9 come into contact with the upper ends of cores 5, so that, as the plate compresses the aggregate, the inner or intermediate cores 5 are correspondingly depressed, as shown in Fig. 4.

Such action depresses the core bridge 4 correspondingly against its supporting springs 12, and at the same time effects an active trowelling movement against the main lower and middle portion of the aggregate, with increasing effect towards the bottom, for the full extent of the stroke. Thereafter, the compression of the aggregate being completed, upward movement of the bottom plate 15 will eject the finished block in the usual way.

Frictional engagement between the inner faces of the block and the main cores 5 will hold them lowered, after the presser plate 6 has been first elevated and thrust out of the way laterally and relieving pressure on the cores by screws 9.

Thereafter, upward ejecting movement of the block will proceed until it and the cores have risen for the amount of spacing between the lowered core bridge and the bottom of the mold, until it re-assumes its normal position under action of springs 12, as in Fig. 5.

The cores 5 are restrained from further upward movement by their connection with the core bridge, as by stud bolts 17. Thereafter, the continued elevation of the block will effect further trowelling action between the inner contacting surfaces and said cores, as well as against the endmost stationary cores, and likewise between the outer faces of the block and the inner faces of the mold, so that, when finally ejected, the block will be completely trowelled and finished, both inside and out.

In this way the commencement of the stripping action, which requires the greatest power, does not effect any frictional rubbing except between the outside of the block and the inside of the mold, by reason of the preliminary accompanying upward movement of the cores themselves.

Upon arresting of the cores, the upward movement having been started is easily continued until the block is finally ejected. This stripping first against the outside surfaces and then against both outside and inside

greatly reduces the required initial power for the stripping operation.

From the foregoing description, it will be observed that when the aggregate is pressed in the mold under lowering action of the presser plate, the compressive action thereof will be at its maximum at the top of the aggregate; that, as the presser plate descends, the downward movement of the particles of the aggregate will steadily decrease toward the bottom of the mass.

That is to say, the upper portion of the aggregate, during such compression or densification, will descend within the mold at a corresponding rate of speed, i. e., with a maximum acceleration at the top, steadily diminishing toward the bottom, where the aggregate is resisted by the stationary pallet and bottom plate.

Likewise, that the trowelling action of the inner faces of the stationary mold and its endmost cores against the outer contacting faces of the aggregate will be effected in the same relatively diminishing ratio, due to the fact of the reducing rubbing action of the aggregate against the mold from its upper maximum activity toward the bottom, where the aggregate is inert.

Such action on the aggregate, varying from maximum at the top to a minimum at the bottom, is indicated by the arrows at the left side of Fig. 2.

On the other hand, due to the lowering movement of the cores, in conformity with the lowering of the presser plate, the cores will descend at a rate of speed equal to that of the descent of the presser plate and with a minimum trowelling action at the top, steadily increasing toward the bottom. This action is due to the fact that the speed of movement of the core in lowering is uniform throughout and its trowelling action is against the inner surfaces of the aggregate under compression, with the maximum of such compression and downward movement at the top, steadily diminishing toward the bottom. The relative rubbing action of the cores, therefore, due to the steadily diminishing downward movement of the aggregate itself, is proportionately and steadily increased toward the stationary bottom of the aggregate as the cores descend.

These effects and the relative degree and extent of such compression and corresponding trowelling movement are illustrated in the diagrams of Figs. 7 and 8. These are for the purpose of showing the difference in the amount of trowelling action which the various portions of the block receive throughout its depth while it is being pressed, both outside and inside. Thus, in Fig. 7, showing the relative amount of exterior trowelling, and assuming the final vertical dimension x of the block is eight inches, from an original depth of loose ag-

gregate of say ten inches, and dividing the block vertically into any arbitrary number of equal vertical sections, as L, M, N and O, it will be observed that, as the compression of the block is effected, its top portion will be lowered with a maximum rubbing or trowelling action against the wall of the mold, decreasing in proportion as the condensation movement decreases toward section M. Likewise, that throughout such section M there is a corresponding decreased compression movement and trowelling action, again repeated in section N, while in section O, the trowelling action steadily diminishes toward the bottom, where it is zero.

On the other hand, due to the fact that the downward movement of the cores is co-extensive with the compression movement of the presser plate on the aggregate, the resulting trowelling action by the core in section L will be in a reverse order, i. e., from zero to a limited degree through section L, then with a greater increase downwardly through section M, a corresponding greater increase through section N, and continuing increase through section O, with the maximum trowelling action at the bottom. This is, of course, because of the steadily decreasing speed of compressive movement of the particles of the block throughout its depth during uniform downward travel of the cores and with a steadily increasing ratio of comparative frictional speed and resulting trowelling, compared to the steadily decreasing compressive action.

Such effect, both as to the outside trowelling against the inner face of the stationary mold and against the relatively movable lowering cores, during compression, is indicated by the shaded lines at the left side of Fig. 7 and right side of Fig. 8 respectively.

As already described, the additional trowelling action by the rubbing of the inside faces of the block against the arrested cores during upward ejection is wholly supplemental and additional to such trowelling during downward movement of the presser plate.

In ordinary molding of aggregate blocks and the like within stationary molds and around stationary cores, the material receives its maximum pressure movement and trowelling action at the top, steadily decreasing towards none at all at the bottom. This results in great variation of consistency, the resulting product being non-uniform, with a tendency to voids, arches, and unequal distribution towards and at the bottom.

By lowering the cores during compression their frictional or trowelling action is imparted laterally through the aggregate in a proportion increasing directly and steadily in the direction of the steadily reducing

compressive movement of the aggregate itself, towards the bottom. The increasing absence of such compressive movement towards the bottom is thus compensated for and provided by the supplemental independent downward movement of the inferior cores during compression.

In its general effect, the rubbing or trowelling action of the cores is progressively greater in the same direction with the increasing inertia of the aggregate, towards the bottom so that a general average consistency is effected throughout the entire depth of the block. This is due to the practically complete disturbance and settlement of the aggregate throughout its entire depth, so that voids etc., are eliminated.

The mixture is more evenly distributed from top to bottom, with a more even texture of body portion throughout, with greater uniformity and density when dry.

Due to such trowelling action, and the more even and better distribution of the aggregate, the surface finish of the block both outside and inside, is greatly improved. A further advantage, as above noted, is in the easier manipulation of the machine, and better distribution of the power applied.

The machine may be changed or varied in different details or in other respects by the skilled mechanic, to adapt it to varied conditions of use or otherwise, but all such changes are to be understood as within the scope of the following claims.

What I claim is:

1. A concrete block molding machine having a mold, a presser plate, a bottom, and a movable core having a spring supported platform.

2. A concrete block molding machine having a mold, a presser plate, a bottom, and a vertically movable core having a spring supported platform.

3. A concrete block molding machine having a mold, a pressure plate, a bottom, and a vertically movable core provided with a fixedly connected transverse spring retracted support.

4. A concrete block molding machine having a mold, a presser plate, a bottom, a vertically movable core provided with a fixedly connected transverse spring retracted support, and means movable with the presser plate for depressing the core.

5. The combination with a mold having an inner supporting bottom, of a resiliently mounted core bridge, a core thereon extending upwardly within the mold, and a presser plate having a portion adapted to engage and depress the core.

6. The combination with a mold having an inner supporting bottom and means for lifting the bottom to eject a pressed block, of a resiliently mounted core bridge, a core mounted on the core bridge extending up-

wardly through the bottom within the mold, and a presser plate having a portion adapted to engage and depress the core.

7. The combination with a mold having an inner supporting bottom and means for lifting the bottom to eject a pressed block, of a resiliently mounted core bridge, a core mounted on the core bridge extending upwardly through the bottom within the mold, and a presser plate having an adjustable portion adapted to engage and depress the core.

8. The combination with a mold having an inner supporting bottom, of a core bridge extending across underneath the mold, supporting stems therefor extending from the mold through the core bridge provided with terminal adjusting nuts and supporting springs, a core mounted on and secured to the core bridge extending upwardly through the bottom within the mold, and a presser plate having a portion adapted to engage and depress the core.

9. The combination with a mold having an inner supporting bottom, of a resiliently mounted core bridge, a core thereon extend-

ing upwardly within the mold, a vertically movable frame provided with a presser plate operable downwardly within the mold, and a screw adjustably mounted in the frame adapted to engage and depress the core as the presser plate descends.

10. In a molding machine of the class described, the combination with an outer mold and an interior core, of means for compressing aggregate within the mold, and means associated with said means and embodying adjustable core moving devices for simultaneously moving the core.

11. In a molding machine of the class described, the combination with an outer mold and an interior stationary bottom support, of means for applying pressure to the contents of the mold from the top towards the bottom, and means embodying adjustable core moving devices for simultaneously applying rubbing action to interior portions of the said contents whereby to assist distribution of the contents under pressure.

In testimony whereof I hereunto affix my signature.

FRANCIS J. STRAUB.
